UNITED STATES PATENT OFFICE.

ISAAC S. PURCELL, OF OAK PARK, ILLINOIS, ASSIGNOR TO TENTOBED COMPANY, OF CHICAGO, ILLINOIS, A CORPORATION OF ILLINOIS.

FOLDING COT.

1,262,600.

Specification of Letters Patent.

Patented Apr. 9, 1918.

Application filed November 15, 1917. Serial No. 202,169.

To all whom it may concern:

Be it known that I, ISAAC S. PURCELL, citizen of the United States, residing at Oak Park, Illinois, have invented certain new and useful Improvements in Folding Cots; and I do hereby declare the following to be a full, clear, and exact description of the invention, such as will enable others skilled in the art to which it appertains to make and use the same.

My invention relates to folding cots, its general objects being to provide a folding cot adapted to be easily erected in rigid fashion, and to be readily folded into comparatively few but compact units. More particularly, my invention aims to provide a folding cot in which all of the constituent elements excepting the cross-braces are permanently connected to each other and yet adapted to be folded into an unusually compact space; in which the side rails may readily be folded upon themselves and then swung against opposite faces of the end rails without disconnecting them from these end rails; in which the legs are permanently carried by the side rails, and in which these legs are adapted to be folded against these side rails, so as to be compacted with the latter when the side rails are folded against the end rails as above described. Moreover, my invention aims to provide a cot frame construction in which each side rail consists of two portions adapted to fold upon each other, and in which the hinge connecting these portions prevents relative lateral movement of the side portion but permits only a limited movement thereof beyond the opening of the folded side rail to a position in which the side rail portions align with each other. Furthermore, my invention aims to provide a cot frame in which the cross bar is locked in position by latching elements engaging the metal hook terminals of the cross bar. My invention also aims to provide simple and strong means for securing the end rails to the said rails while permitting the relative movement thereof when the frame is to be folded into a compact form, and, to provide simple means for tensioning the bed of the cot by imparting one or more quarter-rotations to one of the end rails. Still other objects will appear from the following specification and from

the accompanying drawings, in which drawings—

55

Figure 1 is an end view of the cot and tent-supporting frame of my invention, the tent proper being omitted.

Fig. 2 is a side elevation of the same.

Fig. 3 is an enlarged fragmentary perspective view of a portion of one of the tent-supporting ribs, showing the method of joining the flexible and inflexible parts of such a rib.

Fig. 4 is a transverse section through Fig. 3, along the line 4—4.

Fig. 5 is a plan view of the cot, taken after the tent-supporting frame has been removed from the same.

Fig. 6 is a plan view showing the cot frame as it appears when being folded.

Fig. 7 is a central transverse section through the cot frame when fully folded and when the canvas bed bottom is wrapped around the same.

75

Fig. 8 is an enlarged side elevation of one of the side rails and the legs carried thereby, when completely folded.

Fig. 9 is a plan view of one of the end rails and of the two side rail members 80 folded against opposite faces of the same.

Fig. 10 is a side elevation of a corner portion of the cot frame, showing the arrangement of certain hinges and the socketing of the tent-supporting rib.

85

Fig. 11 is a fragmentary end view of the cot, showing the arrangement of the same hinges and of the latch for one end of a crossbrace.

Fig. 12 is an enlarged fragmentary elevation of the center portion of a side rail and the parts associated therewith, showing the side rail portions swung to their extreme open position.

90

Referring first to the means for supporting a tent or canopy over the cot, this consists of a collapsible frame mounted on the frame of the cot and desirably formed of only two separable parts. Each of these parts, in the embodiment illustrated, includes a pair of ribs pivoted at their upper end to each other and to a ridge piece 1, in combination with foldable braces 2 connecting the ridge piece with the respective ribs. The ridge pieces 1 are preferably made of angle steel and one of them desir-

100

105

ably has at its free end a socket 3 adapted to be entered by the free end of the other ridge piece, after the manner disclosed in my copending application No. 134854. Each 5 of the ribs preferably consists of a substantially inflexible upper portion 4, desirably made of angle steel, and a lower continuation portion 5 made of resilient material and here shown as composed of a bar 10 of round steel. The bar 5 is so joined to the rib part 4 as to aline with the latter when the rib is detached from the cot, for which purpose the upper part of the rod 5 desirably extends through a tubular forma- 15 tion 6 formed by rolling up the lower end of the angle bar 4 (a. in Fig. 3) and terminates in an eye 7 suitably secured to this bar.

To support the tent ribs in operative position, I equip the frame of the cot with upwardly open sockets adapted to receive the lower ends of the bars 5, which sockets desirably include vertical bores extending through the side rails. Being vertical, each 20 of these bores will tend to hold one of the ribs in a vertical position, while the pivotal connection between the ribs will tend to form the latter into a triangle. Consequently, the pair of ribs when thus socketed 25 respectively in the bores of the two opposite side rails will assume the position of Fig. 1, thus affording both a handsomer appearance and a considerably greater effective width than would be obtained with 30 rigid ribs entering oblique sockets as shown in dotted lines. In other words, the ribs rise substantially vertically for some distance from the cot frame, thereby giving a clear width equal to the bed of the cot for 35 a sufficient height to prevent the occupant of the cot from readily contacting with the sides of the tent spread over the ribbed frame.

For the cot itself, I preferably provide a 40 construction comprising only four separable pieces, three of which are equivalent cross-braces. The fourth or main cot portion includes as foldable but permanently connected elements the bed-bottom, the end rails 45 secured to the bed-bottom, the foldable side rails secured to the bed-bottom, the foldable side rails both secured to one of the end rails, and the legs hinged to the side rails. Each side rail preferably consists of two 50 parts 9 and 10 connected by a hinge comprising a trough 11 fastened to the rail 10 and extending beyond the end of the latter, and a plate 12 pivoted to the said trough and fastened to the rail 9, the pivot 13 being 55 normally above the top of both rail portions as shown in Figs. 2 and 12. The trough 11 preferably has its lower or back portion so shaped as to afford a slight bend substantially at its middle, so that when the right 60 hand half of this back is horizontal as

shown in Fig. 12, the left hand half will slope downwardly somewhat. Consequently, the hinge as described will be allowed to open a little more than 180 degrees, thus adapting the cot frame for use on somewhat 70 uneven ground without calling the back of the trough into service for partly supporting the overhanging side rail portion unless the unevenness of the ground is considerable. I also preferably pivot the center legs to the 75 troughs of the hinges, as by riveting a downwardly open U-shaped strap 14 to each of the troughs as shown in Fig. 12, and pivoting the center leg 15 to this strap.

To avoid a separation of the folding cot 80 frame into a large number of parts which might be difficult for a layman to assemble in their proper relation, and equally difficult to secure firmly to each other without the use of tools, I preferably construct this cot 85 frame of two main portions permanently connected by the canvas or bed bottom of the cot, thus leaving as separate and entirely detachable members only the three cross-braces which space the three pairs of laterally opposed legs respectively. For this purpose, I preferably connect the ends of the foldable side rails respectively to end rails 16 and 17 by L-shaped hinges all having shanks extending parallel to the side 90 rails and crossbars extending in one and the same transverse direction as shown in Fig. 5. From this figure it will be obvious that by folding the side rails upon themselves the hinge plates at the ends of each 95 side rail will aline with each other. Then one entire side rail in its folded form may readily be swung against the inner face of the end rail to which it is still and permanently pivoted, while the other folded side 100 rail may be likewise swung against the outer face of the same end rail as indicated in Figs. 6 and 9. Moreover, this can be done without detaching the canvas from either 105 end rail and without detaching either the legs or the braces connecting the legs to the side rail portions. To facilitate this, each center leg 15 and the end leg 19 pivotally connected to the same side rail portion 10 are made short enough to both fold against 110 the under side of this element 10, while each of the other end legs 20 can similarly fold against the under side of the side rail 9, which latter under side becomes a top when 115 the portion 9 is folded over upon the part 120 10. Thus the entire cot frame (with the exception of the three cross-braces 21) folds into the form of Figs. 8 and 9 and permits the canvas bed bottom to be wrapped around these folded parts as shown in Fig. 7. 125

To prevent the strain due to the flexing of the rib elements 5 from gradually enlarging the sockets into which the lower end of these rods 5 are slipped, I preferably use for such sockets, bores alining with corre- 130

sponding perforations in the L-hinge plates 22 and 23 disposed respectively above and below each of the side rail members, so that these bores in the hinge plates will serve instead of bushings for preventing the rod 5 from gradually enlarging the interposed vertical bore in the wood of the side rail part. In so doing, I also desirably use the upper end of the adjacent end leg as a stop 10 for the tip of the rod 5, thereby automatically gaging the latter without requiring additional elements for this purpose.

For the cross-braces, I preferably use wood bars 21 each equipped at each end with a metal plate 25 having at its tip a hook 15 adapted to engage a pin 26 on the adjacent leg, and I likewise pivot the bar 21 to a brace 27 adapted to hook on to another pin or lug 28 placed higher on the adjacent leg 20 than the aforesaid pin 26. To prevent the cross-braces from being loosened out of its normal position (as shown in Fig. 11) I preferably provide a metal latch 29 pivoted to the adjacent leg and arranged for bearing against the upper surface of the hook-plate 25 to maintain the latter in its locked position. To secure the desired tension in the canvas bed bottom and to take up slack or the like in case of a stretching after long 25 use, I preferably provide one of the end rails with a pair of transverse bores either one of which may receive a thumb bolt 18, as shown in Fig. 10, thereby permitting the effective length of the canvas 24 to be increased by wrapping the canvas one or more additional quarter turns around the adjacent 30 end rail. However, while I have thus described a desirable embodiment of my invention including certain details of construction and arrangement, I do not wish to be limited to the same except as implied by the accompanying claims, it being obvious that many modifications might be made without departing from the spirit of my invention. 35

Moreover, having more fully described and claimed the tent-supporting and rib-forming features of my invention in a separate application, filed January 5, 1918 as Serial No. 210,439, I do not here claim these 40 features, although they are desirably employed in connection with the folding features of my cot frame to afford a readily

compacted and effectively hooded cot which will provide an unusual width where the latter is most needed, and which will also afford both a handsome appearance for the hooded structure and an effective watershed in case of rain.

I claim as my invention:

1. A folding cot comprising a bed bottom, 60 a pair of end rails secured to said bottom, and a pair of frame members carrying the said end rails; each of the said frame members comprising a jointed side rail pivoted at one end to one end of an end rail, and legs pivotedly connected to the side rail; the end rails being adapted to be laid one upon another, and the two side members being adapted to have component parts compactly folded and to be thereafter swung about 70 their said pivotal connections to the end rails respectively against opposite faces of the two superimposed end rails.

2. A folding cot construction as per claim 1, including a bed bottom of canvas or the like secured at its ends respectively to the two end rails of the cot, said bed bottom being adapted to be folded upon itself when one end rail is superimposed on the other, and the doubled bed bottom being adapted 80 thereafter to be wrapped around the frame structure composed of the two end rails and the folded side members disposed respectively at opposite sides of the said superimposed end rails.

3. A folding cot as per claim 1, including identical L-shaped hinge plates facing in the same direction and connecting both frame members with one end rail, and thereby adapting the two frame members to be 90 folded respectively against the inner and outer faces of the said end rail.

4. A folding cot as per claim 1, including L-shaped plates fast respectively upon a side rail portion of each frame member and pivoted to the opposite ends of one end rail, the said end rail being equipped for permitting the pivotal connections to be made to it in two relatively transverse positions, whereby the said end rail may be partially 95 rotated to tighten or loosen the bed-bottom 100 of the cot.

Signed at Chicago, October 24th, 1917.
ISAAC S. PURCELL.
